UNITED STATES PATENT OFFICE.

CARL BUECHEL, OF NEW GLARUS, WISCONSIN.

SCAFFOLD-BRACKET.

1,375,078.

Specification of Letters Patent. Patented Apr. 19, 1921.

Application filed July 28, 1920. Serial No. 399,551.

To all whom it may concern:

Be it known that I, CARL BUECHEL, a citizen of the United States, residing at New Glarus, in the county of Green, State of Wisconsin, have invented certain new and useful Improvements in Scaffold-Brackets; and I do hereby declare the following to be a full, clear, and exact description of the invention, such as will enable others skilled 10 in the art to which it appertains to make and use the same.

This invention relates to scaffolds, and more especially to brackets adapted to support the same; and the object of the invention is to produce an improved bracket particularly applicable to shingle roofs.

A further object is to produce an extremely simple and cheap device of this character foldable into as small compass as 20 possible.

Details are set forth below and shown in the drawings wherein:

Figure 1 is a perspective view of one corner of a building showing one use of this 25 invention.

Fig. 2 is a plan view of the bracket itself, showing its tongues in dotted lines as folded.

Fig. 3 is a vertical longitudinal section through the bracket, showing it applied to 30 the shingles of a roof.

This bracket is made up of a base plate 1 formed originally rectangular and with teeth 2 at its lower end which are subsequently bent down as perhaps best seen in 35 Fig. 3 so as to enter the shingles S of a roof, the upper end of the plate constituting a flat lip for insertion under the shingles of a row farther up the roof. Upon said plate a block 3 is secured by bolts 4 and 5, the 40 block having at its upper face a socket 6 for the reception of the tip of a hook H from which a scaffold or painter's ladder L may be suspended as seen in Fig. 1. Overlying the block are two tongues 7 whose lower ends 45 are mounted under the nuts of the upper bolts 5 in such position that these tongues may be swung over the block as indicated in dotted lines in Fig. 2, in which position the bracket may be stored or transported.

When the tongues are swung upward as 50 shown in full lines in this view and in Fig. 3, a scantling or board B may be laid on the base plate against the upper edge of the block and under the tongues, and thus two of these brackets may be used to support a 55 scaffolding upon the roof so that the shingles may be repaired or painted or, in fact, so that the shingles may be applied in case the building is in the course of erection. This use of the device assumes that there are at 60 least two of them, as will be understood. For protecting the block against undue wear, its upper face may be covered with a plate 8 underlying the nuts of the bolts and the lower ends of the tongues, and this plate will 65 be cut out with a considerable opening 9 so as to expose the socket in the block, the walls of said socket by preference tapering downward. Thus if such walls become worn by 70 repeated and careless use of the hooks H whose tips may be jammed into the sockets, the upper plates yet define the mouths of the sockets so that the hooks will not slip from the same.

What is claimed:

As a new article of manufacture, a shingle bracket comprising a metallic base plate whose upper end constitutes a lip for insertion under the shingles of one row and whose lower end is toothed and bent downward for engagement with the shingles of a lower row, a block upon said plate and having a socket in its upper face for the tip of a scaffold supporting hook, a wear plate overlying said face and having an 85 opening surrounding said socket, bolts through the plates and the interposed block, and a pair of tongues pivotally mounted at their lower ends on the upper bolts and adapted to be turned over said plate and 90 block or to be swung into position above said lip.

In testimony whereof, I affix my signature, in the presence of two witnesses.

CARL BUECHEL.

Witnesses:

J. JACOB FIGI,
JACOB S. ACHEN.
